Attorney

UNITED STATES PATENT OFFICE

JOSEPH M. SMYGEL, OF ST. JOSEPH, MISSOURI

BROOM RACK

Application filed April 25, 1931. Serial No. 532,887.

This invention relates to improvements in article supporting racks, and pertains particularly to a rack for supporting a plurality of brooms.

5 The primary object of the present invention is to provide a rack by means of which brooms may be supported from the ends of the handles, in such a manner that any one of the brooms may be removed without disturbing the others on the rack.

10 The invention broadly contemplates the provision of a flat curved body, which may be circular, semi-circular or otherwise formed, in which the edges are provided with recesses which converge slightly from their outer to their inner ends. Means is provided whereby this plate may be suspended in a horizontal position so that the ends of broom handles may be inserted into the recesses and held through frictional engagement in the constricted ends thereof, the support of the brooms further being assisted by the slight enlargement which is found at the ends of the handles of all brooms.

15 A further object of the invention is to provide a broom rack which is of simple but strong and durable construction and which is designed to be economically manufactured.

20 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the 25 appended claims.

In the drawing:

Figure 1 is a view in top plan of a portion of the hanger device embodying the present invention.

30 Figure 2 is a sectional view taken on the line 2-2 of Figure 1.

35 Referring more particularly to the drawing, wherein like numerals of reference indicate corresponding parts throughout the 40 several views, the numeral 1 indicates gen-

erally the body of the rack embodying the present invention, the same here being shown as of circular configuration. It is, of course, to be understood that this rack may be of semi-circular design or of any other of a 55 number of configurations, if desired.

40 In the case of the circular body 1, which is shown, there is formed in the inner and the outer edges thereof the broom handle receiving recesses 2 which are of slightly greater width at their outer ends than at their inner ends, so that when the handle of a broom is inserted it will become wedged slightly in the inner end of the recess. By forming these recesses in the manner shown 45 there are thus formed the fingers 3 and the recesses upon one edge are disposed in staggered relation with respect to those upon the other edge so that those upon one edge are positioned oppositely the fingers between 50 the recesses of the other edge. These fingers 3, while they may be left flat or straight, are preferably turned up slightly adjacent their free ends.

55 Within the annular body 1 there are formed the radially disposed arms 4 which join at the center of the body with a plate 5. This plate 5 supports a center post 6, which has a threaded stem in its lower end which passes through the plate and receives 60 a nut 7.

65 At the upper end of the post 6 is an eye 8 by means of which the support is suspended from a hook, or any other suitable hanger, and at a point beneath the eye 8 there extends radially from the post the curved arms 9, the outer ends of which are provided with reduced threaded extensions 10 which pass through receiving apertures 70 in the body 1 and receive, upon the under-side of the body, the nuts 11.

75 It is, of course, well known that broom handles, at their free ends, are very slightly enlarged and it will thus be seen that, in addition to the frictional engagement of the handle in the constricted portion of one of the recesses 2, this enlargement will prevent the handle passing through the recess. It will also be readily appreciated that with a 80 support of the character herein described 85 90 95 100

any one of a number of brooms suspended therefrom may be readily removed without knocking from position or otherwise disturbing any of the other brooms on the support.

Having thus described the invention, what is claimed is:

1. A broom rack, comprising a flat annular body having a plurality of relatively deep recesses formed in each of the edges thereof, radially disposed arms within the body, connected therewith and joined at their inner ends at the radial center of the body, a post carried by said arms at the radial center of the body, means at the upper end of said post for suspending the structure with the body in horizontal position, and supporting brace arms connecting the body with the post adjacent the upper end of the latter.
2. A broom rack, comprising a flat annular body having a plurality of relatively deep recesses formed in each of the edges thereof, radially disposed arms within the body, connected therewith and joined at their inner ends at the radial center of the body, a post carried by said arms at the radial center of the body, means at the upper end of said post for suspending the structure with the body in horizontal position, and supporting brace arms connecting the body with the post adjacent the upper end of the latter, said body having the portions formed between said recesses turned upwardly and further having said recesses slightly convergent from their outer to their inner ends.

In testimony whereof I hereunto affix my signature.

JOSEPH M. SMYGEL.
